WEB ROLL CONTROLLING MECHANISM

Application filed September 29, 1927. Serial No. 222,745.

This invention relates to certain improvements in web roll changing mechanism for use with multi-couple printing machines.

In certain modern high speed printing press constructions, the presses embody a plurality of printing units each of which prints on a web roll of paper, the webs being delivered or associated in various ways to produce the products required. In the operation of these machines, a large number of copies are run off and the webs have to be renewed from time to time during each run of the press. In operating these machines, it is, of course, of great importance to get out the desired number of products in the shortest time, and it is desirable, therefore, that the operation of the presses shall be interfered with to the least possible degree, particularly during the renewing of the webs. The web rolls used in these machines are supplied by the paper manufacturers in substantially the same sizes, so that when a press is supplied at the start of a run with a plurality of these rolls they will become depleted at or substantially about the same time, so that frequently in a large press several of these rolls have to be renewed at about the same period in the press run.

It is the especial object of the present invention to provide a construction in a multi-roll machine, that is, a machine using at the same time a plurality of web rolls, by which any desired plurality of these rolls may have the expiring webs running therefrom united simultaneously with the new web rolls, this operation being conducted in an entirely automatic manner, that is, new web rolls are joined or spliced to the old webs, the latter severed, and the new rolls placed in running position without necessitating any manual operation.

It is a further object of the invention to provide such a construction in which automatic changing of the rolls is effected or controlled by the decrease in the size of any running roll to a predetermined diameter.

A further object of the invention is to provide such a construction in which, in addition to the automatic changing of the rolls, means is provided for manually effecting a

manipulation of the roll changing mechanism in either direction in the case of an emergency or for convenience in loading, or for any other desired reason.

With these and other objects not specifically referred to in view, the invention consists in certain novel parts, arrangements and combinations which will be described in connection with the accompanying drawings and the novel features pointed out in the claims hereunto annexed.

In these drawings,—

Figure 1 is an end elevation showing more or less diagrammatically a plurality of roll changers and the circuits by which these changers may be operated simultaneously in an automatic manner to paste a plurality of expiring webs and new rolls, and

Figure 2 is a similar view showing a modified form of roll supports for the changers which may be used instead of that illustrated in Figure 1.

Referring now to these drawings, the roll supports and the mechanism for operating the supports are indicated merely diagrammatically, as a detailed showing of all the mechanical connections whereby the parts are operated is unnecessary for an understanding of the invention.

Constructions embodying the invention, however, will include a plurality of roll supports each capacitated to support a spare roll and a roll running to the press, together with means for manipulating the supports simultaneously so that the new rolls, with suitable adhesive applied to the surface thereof, and the webs running to the press may be brought into contact and the new rolls thus pasted to the old webs, the old webs then being severed, the arrangement being preferably such that the depletion of any one of the rolls in use to a predetermined point will automatically effect the cycle of movements required to paste the new rolls to the running webs.

The invention has been shown as embodied in two constructions. Referring first to the construction shown in Figure 1, there is provided a roll support in which the support is manipulated so as to complete a rotation

to bring a spare roll from loading position to pasting and the running position shown, and on the depletion of the roll in running position back to loading position and to pasting and running position with a new roll. 5 In the construction illustrated there is shown two of these roll supports, but it will be understood that as many supports may be provided as is necessary or desired for supplying any desired number of press units. 10 These supports are or may be identical in construction and include standards 200, 201 in which are mounted shafts 202, 203. The shaft 202 supports an arm 204, in the opposite ends of which are bearings 205, 206 for supporting a spare roll S and a running roll R^x, the web from the running roll being indicated by the letter W, this web passing over a guide roll 207 to its press unit (not shown). 15 The shaft 203 supports a similar arm 208, in the opposite ends of which are bearings 209, 210 in which is supported a spare roll S¹ and a running roll R^y. The web from the roll R^y is indicated by W¹ and runs to its 20 press unit (not shown) over a guide roll 211. It will be understood, of course, that arms 204, 208 are duplicated on the other side of the machine. It will also be understood that if desired roll supports capacitated to carry more than two rolls may be 25 used as necessary or desired.

The shafts 202, 203 are operated through suitable motors and circuits so that they may be simultaneously and automatically rotated 30 on the depletion of either the running web roll R^x or the running web roll R^y to move the web rolls S, S¹ into engagement with the webs W, W¹ for pasting these new web rolls to the webs, the movement of the support continuing until the new web rolls are in the desired position for normal running to the press, that is, in the position shown in Figure 1, when the movement of the shafts is automatically stopped until the new web roll 35 has in turn become depleted. While the constructions for effecting this may be somewhat varied, that shown in Figure 1 is a satisfactory one. As shown in Figure 1, full web rolls are indicated in both running position 40 and loading position with the webs running from the upper web rolls or those marked R^x, R^y. Referring to the changer shown at the left of Figure 1, there is provided a controller arm B which rests on the surface of 45 the roll and follows the roll as the roll decreases in size, this arm being mounted on a shaft D, to which is also secured a contact arm C. As the running roll R^x is exhausted, the arm B moves downwardly, swinging the 50 arm C until it engages with contact marked E. 55

When this occurs, a circuit is completed from line L¹, conductor 2, winding of relay R, conductor 3, contact E, contact arm C, shaft D, conductor 4, upper closed contacts of push 60 button switch PL to line L². Relay R be-

comes energized in this circuit and controls an operating motor 64 which acts, through gear connections not shown, to rotate the shaft 202 to the right, as indicated by the arrow A. The circuit for controlling the motor may be traced from the positive side of a line 60, conductor 61, lower closed contacts 62 of relay R, conductor 63, through the winding of motor 64 in the proper direction to cause the shaft to turn to the right, through conductor 65, upper closed contacts 66 of relay R, conductor 67 to the negative side of the line 68. The support, upon turning, causes cam F on the shaft 202 to move past the arm of switch G which is thus allowed to make contact with a contact H. This contact completes a holding circuit for relay R, which circuit extends from line L¹, conductor 2, winding of relay R, through the upper closed contacts K and J, conductor 5, contact H, switch G, conductors 6 and 4, upper normally closed contacts of push button PL to line L². It will thus be seen that as the switch G is in parallel with the switch C the switch C can be opened without interrupting the holding circuit through the relay R, provided the switch G is closed. The support continuing its rotation will cause switch C to open first, but the motor 64 will remain energized in this circuit and will not stop until a second cam F¹, on the shaft 202, strikes switch G and opens the holding circuit, which stops the motor with the parts in the position shown in Figure 1.

With the circuits as described, the roll support is automatically turned to the right, as shown in Figure 1, and this automatic movement of the support will always be to the right. Under some circumstances, it may be desirable to effect a manual control of the support, either to the right or to the left, as, for instance, in an emergency, or for convenience in loading, or for any other desired reason. Means are accordingly provided for doing this, which means may be somewhat varied. As shown, however, the manually operated push buttons PR and PL are provided, and a relay L. The relays R and L together constitute a reversing switch mechanism for the motor 64. When the relay R is energized, the motor operates to turn the support to the right and, when the relay L is energized, the motor operates to turn the support to the left.

The automatic control of the motor to the right is as has been described. For manual operation of the support in the right hand direction, as indicated by arrow A, push button PR is operated. The closing of this button completes a circuit extending from line L¹, conductor 2, winding of relay R, conductors 3 and 7, lower closed contacts of push button PR, conductor 8, back to line L². As long as the push button is held down the support will rotate in a right hand direction.

If it is desired to rotate the support to the left, push button PL is closed, completing a circuit from line L¹, conductor 2, through the winding of relay L, conductor 9, lower closed contacts of push button PL and back to line L². As long as this button is held down the support will rotate towards the left or in the opposite direction to arrow A, as shown in Figure 1. The circuit for this may be traced as follows: From positive line 60 through conductor 212, upper contacts 213 of relay L, conductor 214, through winding of motor 64, conductor 215, lower contacts 216 of relay L, conductor 217, conductor 67 to the negative side of the line 68. It will be observed that the path of the current is in a direction opposite to that it follows when relay R is operated.

It will be understood that the support on the shaft 203 is operated in the same way and that a motor circuit and motor similar to that already described is provided for this changer. In accordance with the invention, means are provided whereby the exhaustion 25 of the running roll in either changer will cause the simultaneous and automatic movement of both changers, so that the running webs are pasted or spliced to the new or spare rolls. Referring again to Figure 1, in which the circuits for this are illustrated with a type of roll support which has a complete rotary movement, the following mechanism and circuits are illustrated.

For the simultaneous operation of the several supports, switches M and M¹ and tie line T are provided. With the running roll R^x, previously referred to, exhausted and switch C closed, an additional parallel circuit is completed from line L², upper closed contacts of push button PL, conductor 4, switch arm C and contact E, conductor 7, upper closed contacts of push button PR, conductor 10, through switch M, conductor T, through switch M¹, conductor 110, upper closed contacts of push button PR¹, conductors 107 and 103, winding of relay R¹, conductor 102 to line L¹. The single web roll being exhausted thus energizes both relay R and relay R¹, the circuit for relay R being the same as previously traced, thus turning both roll supports, and renewing both web rolls at the same time, and, of course, these connections can be extended to operate any desired number of web roll supports.

Relay L^x may be operated independently of relay L by depressing push button PL¹ whereupon a circuit extends from line L¹, conductor 102, winding of relay L^x, conductor 109, lower closed contacts of push button PL¹ to line L². Relay L^x, which is energized in this circuit, completes an energizing circuit for a controlling motor and circuit (not shown) similar to motor 64 to turn the support towards the left. The support may also be independently controlled

to rotate towards the right by depressing push button PR¹, whereupon a circuit is completed from line L¹ conductor 102, winding of relay R¹, conductors 103 and 107, lower contacts of push button PR¹ to line L². Relay R¹ controls at its contacts an energizing circuit for the motor in such a way that the support is rotated towards the right, the circuits being similar to those described with respect to relay R.

Automatic operation may be effected under the control of the support shown to the right in Fig. 1. For instance, when arm B¹ resting on the surface of web roll R^x carries arm C¹ into contact with contact E¹, a circuit is automatically completed for relay R¹ extending from line L¹, conductor 102, relay R¹, conductor 103, contact E¹, arm C¹, pivot D¹, conductor 104, closed contacts of push button PL¹ to line L². This energizes the support control motor similar to motor 64, causing the support to rotate around to the right to replace the roll. A holding circuit for relay R¹ is completed as soon as cam F² passes switch G¹, which holding circuit extends from line L¹, over conductor 102, through winding of relay R¹, through its upper closed contacts K¹ and J¹, conductor 105, contact H¹, switch G¹, conductors 106 and 104, to line L² through the upper contacts of push button PL¹. Relay R will also be energized under these conditions if switches M and M¹ are closed.

The circuit for this relay is traceable from line L¹, conductor 2, winding of relay R, conductors 3 and 7, upper contacts of push button PR, conductor 10, switch M, line T, switch M¹, conductor 110, upper contacts of push button PR¹, conductor 107, contact E¹, switch arm C¹, conductor 104, closed contacts of push button PL¹ to line L².

Thus all the supports may be operated simultaneously and automatically, or any support may be independently operated and in either direction as may be desired, it being understood that the push buttons will operate only the support with which they are associated.

Under some circumstances and particularly where space beneath the presses is confined, it may be desirable to employ a type of web roll support which has an oscillating or swinging movement, and means are provided for simultaneously and automatically operating this type of support to paste or splice a plurality of new web rolls to the webs running to the press units, such an arrangement being shown in Figure 2.

In the construction shown in this figure there is provided for each unit a roll changer in the form of an oscillating support or rack, two of these supports being shown, marked U and V. These supports are similar in construction and are capacitated to carry a running web roll and a spare web roll, and

means are provided for oscillating the supports from running to pasting position and back to running position to effect a pasting or splicing of the spare web rolls to the running webs, the means being such that this movement is automatic. These means will also include connections whereby the supports may be oscillated manually and in either direction for purposes hereafter referred to. While the specific construction of these supports may be varied, the support or rack U is carried on a shaft 225 suitably supported in the framework of the machine, and the support includes a pair of bent arms 226, 227 which carry, in their ends, journals 228, 229 for supporting a running roll R² and a spare roll S², the web from the running roll R² being indicated by W³. Similarly the support or rack V comprises a pair of bent arms 230, 231 which carry supports 232, 233 for a running roll R³ and a spare roll S³, the web from the running roll being indicated by W⁴. The arms 230, 231 are supported on a shaft 234 suitably supported in any desired framework.

In the best constructions, the mechanism hereafter described is operated by the decrease in the running roll to a predetermined size, an actuator, contacting with the roll surface, being used for operating the connections. This actuator, of course, may be of various forms, but in the construction shown it is in the form of a roll 235 which has a sliding movement in a groove 236 in a fixed frame, indicated at 237, one of these actuators being employed for each roll position of each roll changer. These actuator rolls 235 are freely movable in the guides and, contacting with the web roll surface, follow the web rolls as they decrease in size and operate, at a certain predetermined point in the depletion of the running web 4, certain switches and circuits.

Referring to Figure 2, as soon as the left hand roll R² on support or rack U is exhausted, switch W¹⁰ will be operated by actuator roll 235 to close its contact, completing a circuit from line L¹, conductor 31, relay L⁴, conductor 32, contact 33 on switch Z¹, conductor 34, contact 39 on switch Y, conductor 35, upper contacts of push button PR², conductor 36, contact of switch W¹⁰, conductor 37 to line L². Relay L⁴ comprises the circuit to turn the support or rack to the left in order to bring the new roll into pasting position against the running web W³. It will be understood that the start of the movement of the rack to the left will cause the pin 42 to close the switch Z at contact 43, in preparation for the operation of the rack to renew a roll in position S². During the course of this turning, a pin 38 on arm 226 will have engaged the arm 238 of pivoted switch Y, opening the circuit at contact 39, thereby de-energizing relay L⁴ caus-

ing the motor to stop. At the same time, the arm 238 of switch Y engages contact 40, completing a circuit which is traceable from line L¹, conductor 31, winding of relay R², conductor 46, contact 40, switch Y, conductor 35, upper contacts of push button PR², conductor 36, contacts of switch W¹⁰, conductor 37, line L². The energization of relay R² controls the motor to return the support or rack to its normal running position, pin 38^a engaging the arm 238 of switch Y to break the circuit at contact 40. When 38 operates 238, 42 closes Z at 43.

It will be understood, however, that a motor, similar to motor 64, and a circuit therefor, similar to that already described in connection with Figure 1, are provided to operate the support or rack U a sufficient distance to bring the roll S², to which adhesive has previously been applied, into contact with the running web W³ and make the paste.

When the right hand roll S² becomes exhausted, a switch X, by means of one of the actuating rolls, closes its contact and a circuit extends from line L¹, conductor 31, winding of relay R², conductor 46, contact 40 on switch Y¹, conductor 41, contact 43 on switch Z, which would then be closed, conductor 35^a, upper contacts of push button PL², conductor 36^a, contact of switch X, conductor 45, to line L². The motor is thus energized to turn the support or rack U to the right to bring the new roll, which has been loaded into bearings 228, into position to be pasted to the running web at the right. At the same time, pin 38^b on rock arm 227 will have acted on arm 239 of switch Z to open the circuit at contact 43, thus de-energizing relay R² and stopping the motor. However, the lower arm 239 of switch Z will have moved far enough to engage contact 33, establishing a connection extending from line L¹, through conductor 31, winding of relay L⁴, conductor 32, contact 33, arm 239 of switch Z, conductor 35^a, upper contacts of push button PL², conductor 36^a, contacts of switch X, conductor 45, to line L². The support or rack is thus returned to its normal running position, being stopped by the action of pin 42 engaging the arm 239 of switch Z and breaking the contact 33. The push button PR² provides a manual circuit for operating the motor in the right hand direction, the circuit extending from line L¹, conductor 31, winding of relay R², conductors 46 and 47, lower contacts of push button PR², conductors 48 and 37 to line L². Push button PL² is closed to turn the rack to the left, the circuit for relay L⁴ being traced from line L¹, conductor 31, winding of relay L⁴, conductor 44, lower contacts of push button PL², conductor 45 to line L².

When a number of the supports or racks are to be controlled simultaneously, as for

instance U, V, etc., tie-lines T¹ and T² and switches 49^a, 49^b and 149^a and 149^b etc. are provided. Assuming switch W¹⁰ to close upon the exhaustion of the left hand roll R² of rack U, an additional circuit parallel to that above traced is established from line L², conductor 37, switch W¹⁰, conductors 36 and 50, switch 49^a, tie-line T², switch 149^a, conductor 150, upper contacts of push button PR³, conductor 135, switch Y², contact 139, conductor 134, switch Z³, contact 133, conductor 132, relay L⁵, conductor 131 to line L¹. Relay L⁵ is energized to energize the motor (not shown) to move the support or rack V to the left or counter-clockwise in synchronism with rack U. Pin 138, on arm 230, acts on arm 240 of switch Y² to open the circuit at contact 139, de-energizing relay L⁵ and stopping the motor. The lower arm 240 of switch Y² will also have moved far enough to engage contact 140, establishing a circuit that extends from line L¹, through conductor 131, relay R⁴, conductor 146, contact 140, arm 240 of switch Y², conductor 135, upper contacts of push button PR³, conductor 136, switch W¹¹, which at this time is closed by the actuating roll 235 associated with this switch, conductor 137 to line L². The energization of relay R⁴ moves the support or rack back or clockwise to normal running position, pin 138^a engaging the arm 240 of switch Y² to break the circuit at contact 140.

When the right hand roll S², carried in the support or rack U, is depleted to the predetermined point, the supports U, V are both simultaneously operated to paste or join new web rolls which are loaded into the positions R² and R³ to the webs running from the rolls in positions S², S³, and the circuit for effecting this may be traced as follows: A switch X, similar to the switch W¹⁰, is provided, and this switch is operated by an actuator roll 235 associated therewith, the operation of the support being in this instance, clockwise. The circuit for this may be traced as follows: The switch X having been closed by the actuator roll, a circuit is completed from line L¹, conductor 31, relay R², conductor 46, contact 40, conductor 41, contact 43, switch Z, then closed, conductor 35^a upper contacts PL³, conductor 36, switch X to line L², this circuit energizing relay R² and operating support or rack U to the right. Support or rack V is simultaneously operated to the right through a circuit which may be traced from line L² through switch X, conductor 36^a, switch 49^b, tie-line T¹, switch 149^b, conductor 136^a, through the upper contacts of push button PL³, conductor 135^a, contact 143, now closed, switch Z², conductor 141, contact 140 of switch Y³, conductor 146 to relay R⁴, conductor 131, back to line L¹. With this circuit therefore both relays R² and R⁴ are energized and the supports or racks are moved clockwise simultaneously to pasting position.

During this movement, the pins 38^b and 138^b have contacted with the arms 239, 239¹ of switches Z, Z², breaking the circuits at the contacts 43 and 143 and de-energizing the relays R² and R⁴, thus stopping the motors, it being understood that a motor and circuit, similar to the motor 64 and its circuit, previously described, are provided for operating the support or rack V. The downward movement of the switch arms 239, 239¹ of the switches Z, Z² have, however, completed a circuit through contact 33 and 133 for the relays L⁴, L⁵. The circuit for relay L⁴ is the same as that already described when considering the single operation of the support or rack U. The circuit for relay L⁵ is as follows. From line L¹ through conductor 131, through relay L⁵, conductor 132, contact 133 of switch Z², conductor 135^a, upper contacts of push button PL³, conductor 136^a, contacts of switch X¹, which are now closed owing to the arm 231 being moved away, conductor 145 to line L².

In accordance with the invention, means are provided, as before stated, whereby the depletion of a roll in either of the supports or racks U, V will act to automatically operate to effect the pasting operation of all the supports or racks. Consequently, there are shown circuits whereby the depletion of either the roll R³ or the roll S³, shown in the support or rack V at the right of Figure 2, will effect this automatic pasting.

When the right hand roll S³ of support V for instance becomes exhausted, switch X¹ closes its contact through the action of the actuator roll 235 associated therewith, completing a circuit from line L¹, conductor 131, winding of relay R⁴, conductor 146, contact 140 on switch Y³, conductor 141, contact 143 on switch Z², now closed, conductor 135^a, upper contacts of push button PL³, conductor 136^a, contacts of switch X¹ (which are now closed), conductor 145 to line L². The motor associated with support or rack V is thus energized to turn the support or rack V to the right, bringing the new web roll in position R³ into position for pasting. At the same time, pins 38^a and 138^a move switches Y and Y² respectively to engage contacts 39 and 139 in preparation for the operation of changing rolls in positions R², R³. Simultaneously, pin 138^b will have acted on switch Z² to open the circuit at contact 143, thus de-energizing the relay R⁴ and stopping the motor. However, the lower arm 239¹ of switch Z² will move far enough to engage contacts 133, establishing a connection extending from line L¹, conductor 131, winding of relay L⁵, conductor 132, contact 133 of switch Z², conductor 135^a, upper contacts of push button PL³, conductor 136^a, closed contacts of switch X¹, conductor 145 to line L². The support or rack is thus returned counter-clockwise to its normal run-

ning position, being stopped by the action of pin 142 engaging the switch Z^2 and breaking the circuit at contact 133. Push button PR^3 provides a manual control for operating the 5 motor in a right hand direction, the circuit therefor extending from line L^1 , conductor 131, winding of relay R^4 , conductors 146 and 147, lower contacts of push button PR^3 , conductors 148 and 137, to line L^2 . Push 10 button PL^3 is closed for turning the rack to the left, completing a circuit for relay L^5 extending from line L^1 , conductor 131, winding of relay L^5 , conductor 144, lower contacts of push button PL^3 , conductor 145 15 to line L^2 . The depletion of this roll S^3 automatically actuates the roll support or rack V and also simultaneously therewith the roll support or rack U , through a circuit which may be 20 traced as follows: From line L^2 through closed contacts of switch X^1 , conductor 136^a, switch 149^b, tie-line T^1 , switch 49^b, conductor 36^a, upper contacts of push button PL^2 , conductor 35^a, contact 43 of switch Z , 25 now closed, conductor 41, closed contact 40 of switch Y^1 , conductor 46, relay R^2 , conductor 31 to line L^1 .

Assuming the roll R^3 at the left hand position of support or rack V to be exhausted, the 30 automatic movement of this support or rack counter-clockwise to paste a new roll at position S^3 to the web W^4 running from the roll R^3 is effected by the action of actuator roll 235 operating to close switch W^{11} , 35 through the following circuit: From line L^2 , conductor 137, closed contacts of switch W^{11} , conductor 136, upper contacts of push button PR^3 , conductor 135, contact 139 of switch Y^2 , conductor 134, contact 133 of switch Z^3 , 40 conductor 132, relay L^5 , conductor 131 to line L^1 . Through this the relay L^5 energizes the motor to turn the support or rack to the left. This turning movement of the support or rack causes the pin 138 to depress the arm 45 240 of switch Y^2 , breaking the contact at 139 and de-energizing the relay. The downward movement, however, of arm 240 of switch Y^2 has made a circuit at contact 140 of switch Y^2 which energizes the relay R^4 50 to turn the support or rack to the right or clockwise to its normal running position through a circuit, which may be established as follows: From line L^1 , conductor 131, relay R^4 , conductor 146, contact 140 of switch Y^2 , arm 240 of switch Y^2 , conductor 135, 55 upper contacts of push button PR^3 , conductor 136, switch W^{11} , now closed, conductor 137 to line L^2 . The support or rack V may be manipulated to the right or the 60 left manually for purposes of slight adjustments for convenience in loading and the like, by the manually operated push buttons PR^3 , PL^3 , the push button PL^3 when its lower contacts are in circuit energizing the 65 relay L^5 , and the push button PR^3 when its

lower contacts are in circuit energizing the relay R^4 , the relay L^5 turning the support or rack counter-clockwise or to the left, and the relay R^4 turning the rack or support clockwise or to the right, as shown in Figure 70 2, these circuits being similar to those already traced.

The depletion of the roll R^3 acts to automatically rotate the support or rack V counter-clockwise and to simultaneously effect 75 the movement of the support or rack U in the same direction, so that the webs of the new rolls S^2 , S^3 , are pasted or spliced to the rolls W^3 , W^4 running from the rolls R^2 , R^3 . The circuit for effecting this may be established 80 as follows: from line L^2 , conductor 137, closed contacts of switch W^{11} , conductor 136, conductor 150, switch 149^a, tie-line T^2 , switch 49^a, conductor 50, conductor 36, upper closed contacts of push button PR^2 , conductor 35, contact 39 of switch Y , conductor 34, contact 33 of switch Z^1 , conductor 32 relay L^4 , conductor 31 to line L^1 .

The relays L^4 and L^5 are energized to turn the supports or racks to the left or counter-clockwise. This turning movement causes the pins 38, 138 to engage the switch arms 238, 240 of switches Y and Y^2 , breaking the circuits at 39 and 139. This movement of the switch arms, however, makes a circuit at contacts 140 and 40 of switches Y and Y^2 , thus establishing a circuit similar to that already traced for energizing the relays R^2 and R^4 , by which the supports or racks are simultaneously turned to the right or clockwise, looking at Figure 2.

The switches M , M^1 , 49^a, 49^b, 149^a, 149^b 90 may be operated in any suitable or desired manner, either by hand or from a controlling part of the press. As for instance, if a unit 95 were to be discontinued from use, the switch could be connected to the coupling member employed for coupling the unit to the main drive shaft of the press.

It will be observed that with the construction shown and described, a wholly automatic changer has been devised for simultaneously effecting the pasting or splicing of a plurality of webs to a plurality of new rolls, the mechanism for effecting this being controlled by the decrease in the size of any running roll to a predetermined point.

The mechanism for severing the expiring webs after the paste has been made may be of any suitable character and such a severing means has been indicated at 250 in Figure 1 and 251 in Figure 2, it being understood 120 that this mechanism is moved out of the way after the old web is severed.

While the invention has been shown and described in its preferred form, it will be understood that as to certain of its features it has been designed for and can be used with other types of roll supports and, of course, with other circuits for controlling the vari- 125 130

ous mechanisms which might be devised with the purview of the claims hereunto appended.

What we claim is:

1. In a web roll renewer, the combination of a plurality of movable supports each capacitated to support a web roll running to the press and a spare web roll, a relay and circuit for each support for controlling the movement of the support, and tie circuits for causing the simultaneous operation of the relays.

2. In a web roll renewer, the combination of a plurality of movable supports each capacitated to support a web roll running to the press and a spare web roll, a relay and circuit for each support for controlling the movement of the support, any of said relays being controlled by the depletion of any running web roll, and tie circuits for causing the simultaneous operation of the relays.

3. In a web roll renewer, the combination of a plurality of movable supports each capacitated to support a web roll running to the press and a spare web roll, a relay and circuit for each support for controlling the movement of the support, tie circuits for causing the simultaneous operation of the relays, and a second relay for each support and circuits therefor for independently operating the relays.

4. In a web roll renewer, the combination of a plurality of movable supports each capacitated to support a web roll running to the press and a spare web roll, relays for each support, circuits for effecting the automatic and simultaneous operation of the relays, second relays for each support, and manually controlled circuits for effecting the independent operation of the second relays.

5. In a web roll renewer, the combination of a plurality of movable supports each capacitated to support a web roll running to the press and a spare web roll, relays for each support, circuits controlled by the depletion of any running web roll for effecting the automatic and simultaneous operation of the relays, second relays for each support, and manually controlled circuits for effecting the independent operation of the second relays.

6. In a web roll renewer, the combination of a plurality of movable supports each capacitated to support a web roll running to the press and a spare web roll, relays for each support, circuits for effecting the automatic and simultaneous operation of the relays in one direction, second relays for each support, and circuits for controlling the second relays to effect a movement of the supports in the opposite direction.

7. In a web roll renewer, the combination of a plurality of movable supports each capacitated to support a web roll running to the press and a spare web roll, relays for each support, circuits for effecting the automatic

and simultaneous operation of the relays in one direction, second relays for each support, and manually operated circuits for controlling the relays to effect an independent movement of the supports in the opposite direction.

8. In a web roll renewer, the combination of a plurality of movable supports each capacitated to support a web roll running to the press and a spare web roll, a separate motor and circuit for each support for controlling the movement of the support, any of said motors being controlled by the depletion of any running web roll, and tie circuits for causing the simultaneous operation of the motors.

9. In a web roll renewer, the combination of a plurality of movable supports each capacitated to support a web roll running to the press and a spare web roll, a motor for operating each support, a relay and circuit for each motor for controlling the motor, and tie circuits for causing the simultaneous operation of the relays.

10. In a web roll renewer, the combination of a plurality of movable supports each capacitated to support a web roll running to the press and a spare web roll, a motor for operating each support, a relay and circuit for each motor for controlling its movement, any of said relays being controlled by the depletion of any running web roll, and tie circuits for causing the simultaneous operation of the relays.

In witness whereof, we have hereunto set our hands.

HARRY V. BALL.
ALBERT J. HORTON.
